UNITED STATES PATENT OFFICE

2,110,316

PISTON FOR INTERNAL COMBUSTION ENGINES

Alexander M. Alexandrescu, Cleveland, Ohio

Application August 6, 1935, Serial No. 35,001

2 Claims. (CL. 309—8)

The present invention relates to a new and novel construction of piston for internal combustion engines and has for an object to provide an improved type of piston having an upper section to mount the compression rings and one or more oil rings to register with openings in the upper section for passing oil from within the piston therethrough, and to likewise serve for the escape of the oil during the operation of the piston in assuring the proper compression and the release of any smoke or raw gas passed below the compression rings through the openings into the piston to drive the oil downwardly inside thereof.

Another object of the present invention resides in providing a skirt formed in sections adapted to be connected together along with the upper section to form slots or grooves between the sections for the passage of oil from within the piston to engage the cylinder wall, whereby a film of oil for keeping these parts lubricated at all speeds of the engine is attained to assure perfect compression and greater power, and to prevent scarring of the piston in any manner.

A further object of the new piston construction is to provide a new oil and pressure discharging system for the passage of clean oil between the piston and cylinder wall to form a cooling medium for the piston along with the rings and to prevent the usual collection of carbon thereon.

Another object of the new device is to permit the usage of one or more small sized oil rings, and an arrangement of openings cut radially through the piston to communicate with the oil ring grooves and to project substantially half of their width above the rings, whereby the oil may be more freely and advantageously passed back and forth therethrough from the interior of the piston.

A further object of the new piston is to provide a means for lubricating all of the pistons with oil passed through the skirt portions thereof, and to permit for a greater clearance between each piston with the cylinder wall and aid in maintaining better compression.

With the foregoing and other objects in view, the invention will be more fully described herein-after, and will be more particularly pointed out in the claims appended hereto.

In the drawings, wherein like symbols refer to like or corresponding parts throughout the several views.

Figure 1 is a central vertical section through one form of the improved piston construction.

Figure 2 is a transverse section taken along the line 2—2 of Figure 1.

Figure 3 is a central vertical section through a slightly modified form of the piston.

Figure 4 is a transverse section taken along the line 4—4 of Figure 3.

Figure 5 is a central vertical section through another type of slightly modified form of the piston.

Figure 6 is a transverse section taken along the line 6—6 of Figure 5.

Figure 7 is a front elevation of a further modified form of the piston.

Figure 8 is a central vertical section taken along the line 8—8 of Figure 7.

Figure 9 is a transverse section taken along the line 9—9 of Figure 7.

Figure 10 is a transverse section taken along the line 10—10 of Figure 7.

Figure 11 is a fragmentary vertical section of another modified form of the piston, and

Figure 12 is a fragmentary view taken along the line 12—12 of Figure 11.

Referring to the drawings and more particularly to the form of the invention disclosed in Figures 1 and 2 the numeral 10 designates the usual cylinder of an internal combustion engine of any suitable type in which the new construction of piston 11 is mounted to operate.

The piston is advantageously and readily formed to provide sections in which the upper section 12 is shaped to present an inverted cylindrical cup with a closed upper end 13, and having the interior 14 thereof cut away to form an outer and downwardly extending wall 15. This wall 15 is spaced slightly from the cylinder wall 10, and is provided with a plurality of peripheral grooves 16 along the upper portion thereof for inserting the compression rings 17 of a type such as now commonly employed whereby to attain the desired compression in the cylinder.

The lowermost groove 16a is slightly narrower than the grooves 16 to receive the oil ring 11a which is slightly smaller in width than the compression rings 17. The outer walls of the groove 16a are preferably tapered with the upper wall of greater width than the lower wall. A plurality of openings 18 are cut through the upper section 12 to register with the lowermost groove 16a and extend slightly above the same to form vents or leads above the oil ring 11a for the escape of raw gas and smoke into the piston and likewise for feeding the oil through the openings to engage the cylinder wall and to be returned therethrough.

inside the piston under the pressure of the raw gas and smoke.

These openings assure the passage of clean oil to pass therethrough from the interior of the 5 piston to engage the cylinder wall and to be returned during the proper and desired operation of the piston.

The lower portion of the wall 15 has formed thereon the downwardly projecting lugs 19 which 10 are spaced apart, and engage the inner wall of the top section or sleeve 20. The upper edge of the sleeve 20 is held rigidly by the lugs or connection members 19 in spaced relation to the lower edge of the wall 15 to form a series of slots or 15 grooves 21 connected together and to provide a continuous circumferential passageway 21a for the lubricating oil to flow from the interior of the piston to contact with the cylinder wall. This assures a means for readily cooling the upper section or sleeve 20 by the flow of the oil back and forth from the crank case during the operation 20 of the piston.

The intermediate sleeve 22 is rigidly held along its upper edge in spaced relation to the lower edge 25 of the top sleeve 20 by connections or lugs 23 to provide a series of slots or grooves 24 connected together to form the continuous passageway 24a. The lower sleeve 25 is also held in a similar manner by lugs 23 along its upper edge to the lower 30 edge of the intermediate sleeve 22 in spaced relation to form the grooves or slots 26 and to provide the continuous passageway 26a.

The oil from the inner portion of the piston likewise passes through the series of slots 24 and 35 26 arranged along these two circumferential levels to evenly and completely distribute the oil to contact with the cylinder wall whereby to more efficiently cool the piston.

The upper section 12 of the piston is also provided along the lower edge of the wall 15 with a 40 pair of elongated lugs 27 arranged in diametrically disposed relation, and to project downwardly into contact with all of the sleeves or skirt sections. These lugs 27 are secured to these sections and afford an additional means for securely holding the skirt sections in proper alignment. The trunnions 28 are formed upon the lugs 27 and are cut therethrough with openings 29 adapted to support a wrist pin. The series of grooves or 45 slots 24 are advantageously arranged and aligned with the openings 29 whereby to afford means for supplying lubricating oil to the wrist pin.

The form of the piston shown in Figures 3 and 4 shows a slightly modified construction wherein 50 the skirt sections are preferably cut to form a vertical slot 30 which provides a passageway to connect the circumferentially arranged grooves or slots 24 and 26. The slot 30 is provided in the skirt sections to allow the necessary contraction 55 and expansion of the same when overheated in operation, and the slot 30 is arranged to permit these lower sections of the piston to respond independently of the upper section 12 which is spaced therefrom by the circumferential groove 21a. 60 This groove is also advantageous to coat with the circumferential grooves 24a and 26a in stopping the splash of oil from the bearings within the skirt sections, and thus prevent too much oil going into the upper section and passing therethrough about 65 70 the rings.

A furthermore modified type of the piston is disclosed in Figures 5 and 6. The upper skirt section 31, and the lower skirt section 32, are secured together and held to the upper section 12 by 75 practically the same arrangement of connections

or lugs as previously described. The skirt sections are preferably spaced further apart to form a series of wide slots between the same, and to align with the openings formed in the trunnions. The wide slots expose a greater surface of the 5 cylinder wall and allow more oil to circulate therethrough to quickly and more readily cool the skirt sections, and at the same time bring the oil into contact with the wrist pin.

Referring more particularly to the form of 10 the piston shown in Figures 7 to 10 the elongated openings 33 are formed to pass through the piston wall in diametrically disposed relation and placed intermediate the top and the bottom of the skirt portion of the piston. The small circumferential 15 grooves 34 connect with the openings 33 and permit the oil passed from the interior of the piston to circulate uniformly all around the piston and in contact with the cylinder wall. These grooves are advantageously placed within the skirt of the 20 piston for performing the lubrication of the parts since it is readily appreciated that the piston can be fitted within the cylinder with very small clearance. This lends towards keeping the rings 25 steady, for compression, and attains greater cooling results.

The type of piston shown in Figures 7 to 10 can be made with a round skirt as shown, and if desired slightly oval shaped but not sufficient to be intelligently shown on the drawings without exaggerating the same. When the oval shaped type of skirt is formed the diametrically disposed portions of the skirt at right angles to the trunnions presents the elongated or widest portion of the 30 skirt. This portion will contact with the cylinder 35 wall without any clearance, and in having the elongated holes 33 formed in this portion of the skirt the oil is fed therethrough to contact with the cylinder wall to keep the parts properly lubricated.

The piston shown in Figures 11 and 12 shows a 40 different type of connection 35 for holding the upper section and the skirt sections properly spaced apart and in alignment. These skirt sections are preferably rounded adjacent their upper 45 and lower edges 36 to engage with the circumferentially arranged grooves or slots to direct the oil from the crank case more readily and efficiently therethrough for uniformly cooling the skirt sections and the rings. The pair of oil rings 37 are of a smaller size than the compression rings and are mounted below the same with the openings 18 cut through the piston to register 50 and to project beyond the oil ring grooves. These openings 18 afford an efficient means for the 55 passage of oil from within the piston into the oil grooves and to contact with the cylinder wall. The oil is returned through the openings to the inside of the piston around the rings by the force 60 of the raw gas and smoke which is passed downwardly by the compression rings from the engine.

Having thus described my invention what I claim and desire to secure by Letters Patent of the United States is:—

1. A piston for internal combustion engines 65 comprising a closed top, a ring column having inner and outer walls, said ring column having compression ring grooves and an oil ring groove opening through the outer wall, compression and oil rings in said grooves, said ring column having a 70 portion of its outer wall undercut just above the oil ring groove, the under cut portion extending uninterruptedly annually around said piston and forming an annular chamber just above the oil ring, said under cut portion being of much less 75

radial depth than the oil ring groove whereby to leave ample top wall surface for the oil ring groove against which the oil ring engages at its upper side, such top wall surface being continuous all around the piston for the stable support of the oil ring at all points, said ring column having a port substantially radially therethrough opening through both inner and outer walls of the ring column and communicating at its outer side with both the undercut portion and the bottom of the oil ring groove.

2. A piston for internal combustion engines comprising a closed top, a ring column having inner and outer walls, said ring column having 15 compression ring grooves and an oil ring groove opening through the outer wall, compression and oil rings in said grooves, said ring column having a portion of its outer wall undercut just above the oil ring groove, the undercut portion extending 20 uninterruptedly annularly around said piston and

forming an annular chamber just above the oil ring, said undercut portion being of much less radial depth than the oil ring groove whereby to leave ample top wall surface for the oil ring groove against which the oil ring engages at its upper side, such top wall surface being continuous all around the piston for the stable support of the oil ring at all points, said ring column having a port substantially radially therethrough opening through both inner and outer walls of the ring 10 column and communicating at its outer side with both the undercut portion and the bottom of the oil ring groove, a skirt extending in spaced relation to said ring column, and connectors spaced about the circumference of the piston for joining 15 said ring column and skirt, said ring column and skirt having an annular oil channel therebetween for holding oil splashed up from the crankcase.
